UNITED STATES PATENT OFFICE.

EDWARD J. DEITSCH, OF NEW YORK, N. Y.

DESIGN FOR A BELT.

SPECIFICATION forming part of Design No. 30,923, dated May 30, 1899.

Application filed April 3, 1899. Serial No. 711,606. Term of patent 3½ years.

To all whom it may concern:

Be it known that I, EDWARD J. DEITSCH, residing in the city of New York, borough of Manhattan, county and State of New York, have invented and produced a new and original shape or configuration, a Design for a Belt, of which the following is a specification, reference being had to the accompanying drawing, forming part thereof, of which—

10 The drawing illustrates a perspective view of the belt.

A A' represent two parts of the belt. Each of the two parts of the belt consists of an upper and a lower band a a'.

15 b is a knot by which the two parts of the belt are detachably connected together when the belt is not in use.

c c' represent two loops or stays by which the upper and lower bands of the belt are 20 horizontally held at equal distance from the knob b and the buckle ends of the parts A A'.

D represents the buckle of the belt.

The feature of my design consists of a two-

part belt, each of which parts is doubled, rounded, and plaited, and tied or knotted together at the rear central portion of the said parts. The front end of one of the said parts is connected together by means of a piece of leather or other suitable material, carrying a buckle, and the front end of the other part 25 is fastened together by means of a piece of leather having holes therein.

The belt is made of leather, but may be made of any suitable material.

Having described my invention, what I 30 claim as new, and desire to secure by Letters Patent, is—

The design for a belt herein shown and described.

In testimony whereof I have hereunto affixed my signature in presence of two witnesses.

EDWARD J. DEITSCH.

Witnesses:

WILLIAM C. RATH,

JAMES R. ROGERS.
